CLAIM

The ornamental design for vehicle interior seating, as shown and described.

DESCRIPTION

A portion of the disclosure of this patent document contains material which is subject to copyright protection. The copyright owner has no objection to the facsimile reproduction by any one of the patent document or the patent disclosure, as it appears in the Patent and Trademark Office patent file or records, but otherwise reserves all copyright rights whatsoever.

FIG. 1 is a front perspective view of vehicle interior seating, in accordance with the present invention;

FIG. 2 is a front view thereof;

FIG. 3 is a side view thereof;

FIG. 4 is a top view thereof.

FIG. 5 is an opposing side view thereof; and,

FIG. 6 is a rear view thereof.

The stippling that can be seen on the claimed design represents texture of the surface material.

The broken lines showing the environment in the Figures are for illustrative purposes only and form no part of the claimed design.
